UNITED STATES PATENT OFFICE

2,525,322

WINDOW AND SCREEN ASSEMBLY

Joseph Sylvan, Berkley, Mich.

Application May 7, 1945, Serial No. 592,340

18 Claims. (Cl. 160—90)

1

This invention relates to improvements in window and screen assemblies.

More particularly the instant invention relates to improvements in window and screen assemblies wherein the sash frames of the windows and of the screens and the guide channels within which the sashes are supported for slidable movement are preferably formed of metal.

An object is to provide a window and screen assembly which is particularly adapted for use as a storm window and screen assembly. It is designed to be placed permanently within a window opening wherein the windows are supported for vertical slidable travel. The sash of the lower storm window is provided with means to support a screen either in a position overlying the window or in a position elevated above the window. The lower storm window is also provided with means adapted to cooperate with a screen disposed below the window to support the window in the elevated relationship within the window opening.

A further object is to provide a window in such window and screen assembly which has a sash frame the top rail of which is provided with a screen supporting channel extending therealong and projecting inwardly of the inner face of the rail and the bottom rail of which window is also provided with a screen supporting channel extending therealong and projecting inwardly 30 of the inner face of the rail.

A meritorious feature is that the screen supporting channel that extends along the bottom rail of the window sash has a bottom wall that projects inwardly and downwardly at an acute angle to the plane of the rail and defines a space within which the top rail of a screen may be received to support the window in the elevated position and to maintain tight fitting engagement between the window and the screen.

A further object is to provide a screen for this window and screen assembly which is adapted to be supported by the lower window or to support the window and which is adapted to cooperate with the window to form close fitting engagement between the screen and the window. This screen is provided with side rails which have flange portions that form contact below the window with the outer wall of the guide channel within which the window is disposed for slidable movement. Such contact between the flange portions of the side rails of the screen and the wall of the guide channel below the window is to provide a fly-tight seal between the screen and the window frame within which the screen is mounted below the window.

2

A further object is to provide a window with a metal sash the side rails of which are laterally adjustable to accommodate the window to window openings which vary slightly in size and which window sash includes supplemental top and bottom rails which are manually adjustable to maintain the side rails at their laterally adjusted positions.

A meritorious feature of the metal guide channel within which the windows are slidably mounted is that it has a plate associated therewith which is vertically adjustable to form tight fitting contact with the sill of the window frame within which the guide channel is mounted.

Other objects, advantages and meritorious features of the invention will more fully appear from the following description, appended claims and accompanying drawings, wherein:

Figure 1 is a front elevation of a window frame 10 within which the improved window and screen assembly is mounted.

Figure 2 is a vertical sectional view taken on the line 2—2 of Figure 1 showing the screen supporting the lower storm window in the elevated out-of-use position.

Figure 3 is a vertical sectional view taken on the same line as Figure 2 but showing the lower storm window supporting the screen in the elevated out-of-use position.

Figure 4 is a horizontal sectional view taken on the line 4—4 of Figure 3.

Figure 5 is a fragmentary horizontal cross sectional view taken on the line 5—5 of Figure 2.

Figure 6 is an elevation of a fragment of a screen such as is shown in Figures 2 and 3.

Figure 7 is an elevation of the fragment of the screen shown in Figure 6 but taken from the opposite side.

Figure 8 is a horizontal sectional view taken on the line 8—8 of Figure 7.

Figure 9 is a vertical sectional view taken on the line 9—9 of Figure 6.

Figure 10 is a perspective of a corner fragment of the screen.

Figure 11 is an elevation, partly broken away, of a storm window of the character shown in the drawing.

Figure 12 is a view taken on the line 12—12 of Figure 11 being partly in perspective and partly in section.

Figure 13 is a fragment of the lower end of the guide channel within which the window is supported for vertical slidable movement showing the guide channel adjustable plate.

The window and screen assembly here shown is illustrated as supported within a window opening

in a building structure 20. This window opening is shown as defined by a sill 22, a header 24, and vertical jamb pieces 26. This window opening is provided with the usual conventional vertically slidable windows 28 and 30. The jamb 26 is provided with an outer stop 32, a parting stop 34 and a suitable inner stop 36 to guide the windows 28 and 30 in their slidable movement. These windows form no part of the invention.

The invention resides in the window and screen assembly which is here shown as a storm window and screen assembly. It includes a pair of complementary upright guide channels 38 formed of sheet metal and connected at the top by a channel shaped header 40 forming an inverted U-shaped structure when disposed within the window opening. This U-shaped structure is disposed inverted within the window opening. The header member exhibits an upwardly open channel portion 42 which is received over the header stop within the window opening as shown in Figures 2 and 3.

The upright side guide channels 38 exhibit outwardly open channel portions 44 which are received over the stops 32 to secure the structure within the window opening. Each side member 38 exhibits a pair of inwardly open guide channels within which the two storm sash 46 and 48 are supported for vertical slidable movement. The upper and outer storm sash 46 is supported within the outer of these guide channels and the lower and inner storm sash 48 is supported within the inner of these guide channels. The outer side wall of the inner guide channel, which is formed by a fold 50 in the sheet metal strip that is bent to form the guide channel upright frame piece, has a width greater than the inner side wall of the inner guide channel as will appear from Figure 4 for a purpose hereinafter set forth.

In order to accommodate this guide channel structure within window openings which may vary somewhat in vertical dimensions or wherein the sill may vary as to its angle a metal plate 52 is received within the fold 50 and is vertically adjustable therein to form contact with the sill as shown in Figures 1 and 13.

The lower window 48 is provided with a metal sash which includes a channel shaped top rail 54 and a channel shaped bottom rail 56 each of which extends along and embraces a margin of the glass pane. A supplemental bottom rail member is secured to the bottom rail 56 and exhibits an upwardly open channel portion 58 the bottom wall 60 of which projects inwardly and downwardly from the inner face of the bottom rail of the window at an acute angle as shown in Figures 2 and 3. This supplemental bottom rail member has a channel portion 62 which embraces and extends along the bottom rail 56 of the sash 48 to secure the same thereto.

A supplemental top rail member is secured to the top rail 54 of the sash. This supplemental top rail exhibits an upwardly open channel 64 and a downwardly open channel 66 which embraces the top rail 54 as shown in Figures 2 and 3. Each of these supplemental channel rail members is secured to its sash rail in such a manner as to be adjustable lengthwise therealong and to frictionally retain its position of adjustment thereover.

A side rail 68 of channel shape embraces and extends along each vertical side margin of the glass pane as shown in Figures 11 and 12. Each side rail overlaps at the ends the top and bottom rails 54 and 56. The supplemental top and bottom rails heretofore described embrace the top and

bottom rails 54 and 56 between the two side rails 68. Each side rail 68 has a portion 70 extended over the end of the top rail or bottom rail so as to complete the frame.

Each side rail is adjustable laterally with respect to the top and bottom rails and with respect to the glass pane as shown in Figure 11. Each side rail may be withdrawn horizontally relative to the top and bottom rails and the supplemental top and bottom rails may be shifted as shown in Figure 11 so as to hold a side rail at its adjusted position. Due to this adjustment of the side rails it is possible to accommodate a window to the proper width of opening to form a tight fit within the window frame opening while permitting slidable movement of the window. Such window frame openings differ somewhat in size and with a wooden sash it is customary to cut them to fit at the time of installation. This metal sash may be adjusted as above described at the time of its installation.

As seen in Figures 1, 2 and 3, a screen which is indicated as a unit as 72 is adapted to be supported within the channel 64 of the supplemental top rail member to extend above the window 48. This screen may be positioned underneath the bottom wall 60 of the channel 58 of the supplemental bottom rail member as shown in Figure 2 to support the window in the elevated relationship. When the screen 72 has its bottom rail seated within the channel 64 of the top rail of the lower window as shown in Figure 3 the lower window may be raised until the top edge of the screen contacts the window header frame piece which will limit the elevation of the lower window beyond a small distance sufficient for ventilation but insufficient for unauthorized entrance.

When the screen unit is positioned with its top rail abutting the bottom wall 60 of the channel of the bottom rail of the window 48 it serves to support the window in the elevated position as shown in Figure 2 and permits full ventilation through the lower half of the window frame. The projection of the bottom wall 60 of the channel 58 at an acute angle to the bottom rail of the window forms tight fitting contact with the top rail of the screen and holds the same snugly against rattle and constitutes a fly-tight seal.

The screen itself may be of the form shown in Figures 6 through 10 of this application. The screen illustrated in Figures 6 through 10 comprises a sash frame having a top rail 74, bottom rail 76 and complementary side rails 78 secured together at their corners to form a rectangular frame with screen wire mesh 80 stretched across the opening in the frame and secured thereto. Each sash rail has its inner margin bent outwardly upon itself forming a flange 82 which extends outwardly away from the margin at an acute angle to the plane of the rail as shown in Figures 8 and 9. The screen wire 80 is folded over this flange and a channel strip 84 is received over the fold in the wire and over the edge of the flange and extends therealong all as shown in Figures 6 through 10. These channel strips not only secure the screen wire mesh in place but stretch it taut across the opening and hold it stretched thereacross. One side wall of each channel strip 84 is folded over at the corner as at 86 (Figure 10) over its cooperating channel strip to form a continuous retainer about the opening in the sash.

The screen sash is here shown as having each side rail provided at both ends with an extension 88. One of these end extensions folds over the

top rail 74 and the other end extension folds over the bottom rail 76 as shown in Figures 6, 7 and 10 to secure the ends of the rails together to form the rectangular sash. Each side rail 78 is so shaped by being folded upon itself as to exhibit a flange 90 which extends normal to the plane of the screen and away from the rail on the side opposite the flange 82 as shown in Figures 2, 3, 8, 9 and 10. This flange 90 has a width equal to the width of the inner guide channel within which the lower window 46 is adapted to travel so that when the screen is supported either above the lower window or below such window the flanges 90 extend across this channel and engage the outer wall of the channel as shown in Figure 4 forming a fly tight fit therewith. These flanges 90 are of such a length as to terminate short of the bottom margin of the bottom rail 76 of the screen as shown in Figure 3 so that when the bottom rail 76 is seated within the channel 64 as shown in Figure 3 the flanges 90 extend across the top rail of the lower window 48. When the screen is placed below the window to hold it in the elevated position as shown in Figure 2 it is inverted, that is the rail 76 is used at the top and the flanges 90 extend underneath the window as shown in Figure 2.

The screen may be used to hold the inner window in the elevated position as shown in Figure 2 or the screen may be placed in an out-of-the-way position above the lower window as shown in Figure 3. In Figure 3 the upper window 46 might be lowered if ventilation was desired through the upper half of the window or the screen might be disposed as here shown for out-of-the-way disposition as in the winter time when both storm sash are in use. Obviously if desired the screen might be supported within the channel 58 and the lower window partly elevated or completely elevated in which the position the screen would not be in use.

This particular assembly is capable of being readily installed within a window opening and of being left permanently in place and is adapted to serve the demands of both winter and summer use. It represents an attractive, neat appearance and is of such a compact construction that it is receivable within a relatively small space so as to fit any conventional window opening.

What I claim is:

1. In a window and screen assembly, a window and its sash supported for raising and lowering within spaced complementary guide channels of a window frame, the top rail and the bottom rail of the window sash each being provided with an upwardly open channel extending along and projecting inwardly from the inner face of said rails, and a screen having a sash the bottom rail of which is receivable within either of said upwardly open channels to be supported thereby.

2. In a window and screen assembly, a window and its sash supported for raising and lowering within spaced complementary guide channels of a window frame, the top rail and the bottom rail of the window sash each being provided with an upwardly open channel extending along and projecting inwardly from the inner face of said rails, the bottom wall of the bottom rail channel projecting downwardly and inwardly from the plane of the rail at an acute angle thereto, a screen having a sash rail receivable within either of said channels and receivable within the space between the bottom rail and the bottom of the channel extending therealong to support the window in the elevated position.

3. In a window and screen assembly, a window and its sash supported for raising and lowering within spaced complementary guide channels of a window frame, said frame having a downwardly open channel shaped header connecting said guide channels at the top, the top rail and the bottom rail of the window sash each being provided with an upwardly open channel extending along and projecting inwardly from the inner face of said rails, and a screen having a sash rail receivable within the upwardly open channel that extends along the bottom rail of the window sash to support the screen overlying the window and also receivable within the upwardly open channel that extends along the top rail of the window sash to support the screen to project upwardly above the window, the vertical height of the window opening between the guide channels and below the header being slightly greater than the combined effective vertical height of the window sash and screen when the screen is supported seated within the channel of the top rail of the window sash.

4. A window and screen assembly comprising, in combination, a window sash supported for raising and lowering within a frame having complementary upright channel guides within which the window is mounted to travel, the outer side wall of each channel guide being of greater width than the inner side wall of the guide, the top rail of the window sash being provided with an upwardly open channel extending along and projecting inwardly of the inner face of the rail, a screen having sash side rails provided with angular flanges of a width substantially equal to the width of the guide channels within which the window is mounted, said flanges terminating a spaced distance above the bottom margin of the bottom rail of the screen sash substantially equal to the distance the bottom of the upwardly open channel of the top rail of the window sash is spaced below the top margin of said top rail.

5. A window and screen assembly comprising, in combination, a window sash supported for raising and lowering within a frame having complementary channel guides within which the window is mounted to travel, each channel guide having an outer side wall of greater width than its inner side wall, the top rail and the bottom rail of the window sash each provided with an upwardly open channel extending along and projecting inwardly of the inner face of the rail, said upper channel being spaced from the upper margin of the window and said lower channel being spaced from the bottom margin of the window substantially equal distances, a screen having a sash rail receivable within either of said channels, said screen sash having side rails provided with flanges of a width substantially equal to the width of the guide channel within which the window travels, said flanges terminating a spaced distance from the bottom of the screen substantially equal to the spacing of the said channels from the adjacent end margins of the window.

6. A window sash having a top rail and a bottom rail each provided with an upwardly open channel portion projecting inwardly from the inner face of the rail.

7. A window sash having a bottom rail provided with an upwardly open channel projecting inwardly from the inner face thereof and with the bottom of the channel projecting inwardly and downwardly at an acute angle to the inner face of the rail.

8. A window sash having a bottom rail provided with an upwardly open channel projecting inwardly from the inner face thereof and with the bottom of the channel projecting inwardly and downwardly at an acute angle to the inner face of the rail and terminating spaced above the bottom margin of the rail.

9. A window and screen assembly comprising, in combination, a window frame having complementary upright channel guides, a window supported for raising and lowering within said guides, the outer side wall of each channel guide being of greater width than the inner side wall of the guide, a screen adapted to be mounted within the frame below the window when the window is elevated and above the window when the window is lowered, said screen having sash side rails provided with angular flanges of a width adapted to project across the channel within which the window is mounted and to engage the outer side wall of the channel guide.

10. A window screen sash having a side rail formed of sheet metal the inner margin of which is bent upon itself forming a flange projecting outwardly away from said margin at an acute angle to the plane of the sash rail and the outer margin of which is bent forming a flange projecting normally away from the plane of the rail and in the opposite direction therefrom to that of the first flange.

11. A window screen sash having a side rail formed of sheet metal the inner margin of which is bent upon itself forming a flange projecting outwardly away from said margin at an acute angle to the plane of the sash rail and the outer margin of which is bent forming a flange projecting normally away from the plane of the rail and in the opposite direction therefrom to that of the first flange, said last named flange terminating at one end short of the end of the screen sash.

12. A window sash of the character defined in claim numbered 6 wherein the bottom of the upwardly open channel of the top rail is spaced below the top margin of the top rail and the bottom of the upwardly open channel of the bottom rail is spaced above the bottom margin of the bottom rail.

13. A window sash and screen assembly comprising, in combination, a window sash supported for raising and lowering within a frame structure, such sash having a top rail provided with an upwardly open channel portion offset laterally of the plane of the window, a screen having a bottom rail receivable within the channel of the top rail to support the screen upon the window, such screen having side rails provided with flanges projecting normally to the plane of the screen, said flanges having a width substantially as great as the thickness of the top rail of the window sash and terminating spaced above the bottom margins of the bottom rail of the screen.

14. A window sash and screen assembly comprising a window sash supported for raising and lowering within a window frame structure, said sash having a bottom rail provided with a part extending therealong and projecting inwardly

and downwardly from the plane of the rail, a screen having a top rail receivable between said part and the opposing surface of the bottom rail of the window, said screen having side rails provided with flanges projecting normally to the plane of the side rails, each said side rail flange having a width substantially as great as the thickness of the bottom rail of the window sash.

15. A window screen sash having two side rails connected at the top by a top rail and connected at the bottom by a bottom rail, each side rail provided with a flange extending therealong and projecting normally to the plane thereof, and terminating at the ends spaced from the top and bottom margins of the top and bottom rails of the screen sash respectively.

16. In a window sash and screen assembly, a window and its sash supported for raising and lowering within spaced apart complementary guide channels for the window frame, the top rail of the window sash being provided with a laterally offset upwardly open channel extending therealong, the bottom rail of the window sash being provided with a part extending lengthwise therealong and projecting laterally therefrom and forming a downwardly open channel, a screen having a bottom sash rail receivable within the channel of the top rail of the window sash to support the screen thereabove, said screen having a top sash rail receivable within the downwardly open channel of the bottom rail of the window sash to support the window in the elevated position.

17. A window and screen assembly comprising, in combination, a window sash supported for raising and lowering, said sash having a top rail provided with a laterally offset upwardly open channel part extending lengthwise therealong and adapted to receive the bottom rail of a screen to support the screen above the sash and a screen provided with a bottom rail receivable within said channel.

18. A window and screen assembly comprising, in combination, a window sash supported for raising and lowering, said sash having a bottom rail provided with a laterally offset downwardly open channel part extending lengthwise therealong and adapted to receive the top rail of a screen to support the sash above the screen and a screen having a top rail receivable within said channel.
